FOLDABLE AND ADJUSTABLE FLOWER POT SUPPORT OR THE LIKE

Ralph Cucullo, 118 Mount Joy Place,
New Rochelle, N.Y.

Filed June 19, 1963, Ser. No. 75,422

Term of patent 14 years

(Cl. D35—3)

FIG. 1.

FIG. 2.

FIG. 3.

FIG. 4.

FIGURE 1 is a perspective view of a foldable and adjustable flower pot support or the like showing my new design;

FIG. 2 is a top plan view thereof;

FIG. 3 is a front elevation in closed position; and

FIG. 4 is a top plan view thereof in closed position.

I claim:

The ornamental design for a foldable and adjustable flower pot support or the like, as shown.
